UNITED STATES PATENT OFFICE

149,952

DESIGN FOR AN APPLICATOR FOR LIP
ROUGE OR THE LIKE

Ralph E. Kruck, Clinton, Conn.

Application April 14, 1947, Serial No. 138,370

Term of patent 14 years

(Cl. D86—10)

To all whom it may concern:

Be it known that I, Ralph E. Kruck, a citizen of the United States, residing at Clinton, in the county of Middlesex and State of Connecticut, have invented a new, original, and ornamental Design for an Applicator for Lip Rouge or the like, of which the following is a specification, reference being had to the accompanying drawings, forming part thereof.

Fig. 1 is a perspective view of the applicator for lip rouge or the like showing my new design; and

Figs. 2 and 3 are longitudinal sectional views through the applicator shown in Fig. 1 on a smaller scale and in planes at right angles to one another.

I claim:

The ornamental design for an applicator for lip rouge or the like, as shown.

RALPH E. KRUCK.
